(57) **CLAIM**

The ornamental design for a compartmentalized container, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a perspective view of a compartmentalized container, showing my new design;

FIG. 2 is a perspective view thereof, shown in partially open condition;

FIG. 3 is a perspective view thereof, shown in an open condition;

FIG. 4 is a first exploded perspective view thereof, shown in an open condition;

FIG. 5 is a second exploded perspective view thereof, shown in an open condition; and,

FIG. 6 is a third exploded perspective view thereof, shown in an open condition.

The broken lines are shown for the purpose of illustrating parts of the article that form no part of the claimed design. The dot-dash broken lines of FIGS. 4-6 are included to show the relationship between portions of the compartmentalized container and form no part of the claimed design.

1 Claim, 6 Drawing Sheets
